JOHN H. JEPSON, OF MINNEAPOLIS, MINNESOTA

KNEE LOCK FOR ARTIFICIAL LEGS

Application filed August 22, 1929. Serial No. 387,679.

My present invention has for its object the provision of a simple and highly efficient manually controlled knee lock for an artificial leg, for a disarticulation at the hip, or for an amputation above the knee that leaves the stump so short that the patient cannot control the movement of the artificial leg with which he is fitted and particularly when he is learning to walk or when going down stairs. By the use of this knee lock, the lower leg section may be locked at will to the upper leg section of the artificial leg, thus causing the patient to walk stiff legged, but at the same time it gives him control over the movement of the artificial leg.

To the above end, the invention consists of the novel devices and combination of devices hereinafter described and defined in the claims.

In the accompanying drawings, which illustrate the invention, like characters indicate like parts throughout the several views.

Referring to the drawings:

Fig. 1 is a fragmentary view in front elevation showing an artificial leg at the knee joint for an amputation above the knee and having the invention embodied therein;

Fig. 2 is a view partly in side elevation and partly in section taken on the line 2—2 of Fig. 1;

Fig. 3 is a fragmentary detail view with some parts sectional on the irregular line 3—3 of Fig. 1, on an enlarged scale;

Fig. 4 is a perspective view of the anchor plate, on an enlarged scale, removed from the upper leg section, and with the knee lock removed therefrom;

Fig. 5 is a fragmentary perspective view of the lock plate, on an enlarged scale, and removed from the lower leg section; and

Fig. 6 is a fragmentary detail view with some parts sectional on the line 6—6 of Fig. 2, on an enlarged scale.

The numerals 7—8 indicate the upper and lower sections of an artificial leg, for an amputation above the knee, connected by a knee joint 9 which section and knee joint may be of standard or any well-known construction.

The knee lock includes a vertically disposed main lever 10 intermediately fulcrumed at 11 to a pair of laterally spaced rearwardly projecting bearing flanges on an anchor plate 13 and between which flanges said lever extends and is held thereby against lateral shifting movement. This anchor plate 13 is fitted to the inner surface of the upper leg section 7 and rigidly secured by nut-equipped bolts 15 to said section. The knee lock, as shown, is at the front and transverse center of the artificial leg and the fulcrum 11 is substantially at the same elevation as the axis of the knee joint 9.

Formed on the lower end of the lever 10 is a wide forwardly projecting hook or detent 16 which works through an aperture 17 in the upper leg section 7 for cooperation with a lock plate 18. This lock plate 18 is fitted to the inner surface of the lower leg section 8, rigidly secured thereto by rivets 19 or other fastening devices, and is provided near its top with an aperture 20 into which the detent 16 projects when in operative position for engagement with the lock plate above said aperture to connect the two leg sections 7 and 8, thereby holding the same stiff when straight. The lower leg section 8 at the aperture 20 is recessed at 21 to afford clearance for the detent 16.

A simple control is provided for the main lever 10, operable from the exterior of the leg to move the detent 16 into or out of interlocking engagement with the lock plate 18. This control is in the form of a short wide lever 22 in bell-crank arrangement with main lever 10, and its inner arm is bifurcated to receive, between its prongs, the transversely reduced inner arm of the main lever 10, which works therebetween and is attached thereto by a cam connection. Said cam connection, as shown, comprises a longitudinally extended slot 24 in the inner arm of the main lever 10, and a cam pin 25, which extends through said slot and is anchored to the prongs of the secondary lever 22. The outer arm of the secondary lever 22 works in an aperture 26, in the upper leg section 7 at the front thereof.

A latch 27 and cooperating stop lug 28 are

100

provided for holding the secondary lever 22 with a detent 16 in either an operative or an inoperative position. This latch 27 in is the form of a flat member, which extends transversely of the secondary lever 22, is mounted in a channel-like seat 29 formed therein and intermediately pivoted at 30 to said lever. A coiled spring 31 mounted in spring seats in the long arm of the secondary lever 22 and latch 27, yieldingly holds said latch in an operative position. The stop lug 28 is formed with the anchor plate 14, extends in the path of movement of the short end of the latch 27 and holds the secondary lever 22 with the detent 16 in either an operative or an inoperative position.

When the latch 27 is above the stop lug 28, the detent 16 is in an operative position in which it interlocks with the lock plate 18 and holds the leg sections 7 and 8 stiff and when said latch is below said lug, it holds the detent 16 in an inoperative position, as indicated by broken lines in Fig. 2. This latch 27 extends slightly outward of the outer face of the upper leg sections 7 where the same may be easily manipulated by the patient through his clothing to release said latch from the stop lug 28 by a lifting movement thereof, into a position in which it will pass over the stop lug 28 during the movement of the secondary lever 22. Said latch 27 also affords a convenient finger piece on the secondary lever 22 by which it may be manipulated to operate the main lever 10, hence the detent 16.

For the purpose of this case it is not thought necessary to illustrate the knee control except the flexible connection 32 between the leg section 7—8 at the back thereof which has a slight longitudinal stretch, limits the forward swinging movement of the lower leg section 8 in respect to the upper leg section 7 and stops the same when properly aligned with said upper leg section. This connection 32 may be of any well-known construction. The relation between the detent 16 and lock plate 18 is such that the connection 32 must be placed under slight tension by a backward bending of the leg at the knee joint to cause the lock detent 16 to enter the aperture 20 in the lock plate 18. This tension under which the member 32 is placed securely holds the detent 16 interlocked with the latch plate 18 so that there is no lost motion therebetween.

From the above description, it is evident that the above described knee lock may be easily operated by the patient through his clothing to render said lock either operative or inoperative at will. Furthermore, the knee lock is substantially entirely encased within the leg so that it does not have any protruding parts that would hold that patient's clothing away from the leg and thus be conspicuous.

What I claim is:

1. The combination with the upper and lower sections of an artificial leg, and a knee joint connecting the same, of a lock for the knee joint within said leg for holding the sections thereof stiff when in a predetermined position, said lock comprising a main lever pivoted intermediate of its ends to the upper leg section and a secondary lever pivoted intermediate of its ends to the upper leg section, said two levers being at an angle to each other, a positive cam connection between the inner arms of said two levers, said main lever having a detent on its outer arm, the outer arm of the secondary lever being arranged where the same may be manually operated from the exterior of said leg, a lock plate on the lower leg section arranged to be engaged by the detent for holding the leg section stiff when in a predetermined position, a movable latch member on the outer arm of the secondary lever, and a cooperating stop lug on the upper leg section for positively holding the secondary lever with the main lever in a position in which its detent is interlocked with the lock plate. 70 75 80 85 90

2. The combination with the upper and lower sections of an artificial leg, and a knee joint connecting the same, of a lock for the knee joint within said leg for holding the sections thereof stiff when in a predetermined position, said lock comprising a main lever pivoted intermediate of its ends to the upper leg section and a secondary lever pivoted intermediate of its ends to the upper leg section, said two levers being at an angle to each other, a positive cam connection between the inner arms of said two levers, said main lever having a detent on its outer arm, the outer arm of the secondary lever being arranged where the same may be manually operated from the exterior of said leg, a lock plate on the lower leg section arranged to be engaged by the detent for holding the leg section stiff when in a predetermined position, a movable latch member on the outer arm of the secondary lever, and a cooperating stop lug on the upper leg section for positively holding the secondary lever with the main lever in a position in which its detent is either interlocked with the lock plate or released therefrom. 95 100 105 110 115

3. The combination with the upper and lower sections of an artificial leg, and a knee joint connecting the same, of a lock for the knee joint within the leg for holding the sections thereof stiff when in a predetermined position, said lock comprising a main lever and a secondary lever, each of which is pivoted intermediate of its ends to the upper leg section, and a lock shoulder on the lower leg section, said two levers being substantially perpendicular to each other and in the same plane with their inner arms directly connected for compound pivotal and sliding 120 125 130

movements, the one upon the other, said main lever having a detent on its outer end constructed and arranged to interlock with the lock shoulder, the outer arm of the secondary lever being arranged whereby the same may be manually operated from the exterior of the leg.

In testimony whereof I affix my signature.
JOHN H. JEPSON.
